(57) **CLAIM**

The ornamental design for a blower motor, as shown and described.

DESCRIPTION

FIG. 1 is a left plan view of a preferred embodiment of the present invention;

FIG. 2 is a right plan view of the preferred embodiment of the present invention;

FIG. 3 is a top plan view of the preferred embodiment of the present invention;

FIG. 4 is a bottom plan view of the preferred embodiment of the present invention;

FIG. 5 is a cross-section taken along line 5—5 of FIG. 4 of the preferred embodiment of the present invention;

FIG. 6 is a front plan view of the preferred embodiment of the present invention;

FIG. 7 is a back plan view of the preferred embodiment of the present invention;

FIG. 8 is a front perspective view of the preferred embodiment of the present invention; and,

FIG. 9 is a back perspective view of the preferred embodiment of the present invention.

The broken lines shown in the drawing are for illustrative purposes only and form no part of the claimed design.

The broken line showing of portions of the blower motor is included for the purpose of illustrating environmental structure and forms no part of the claimed design.
